HEAT RESPONSIVE MEANS FOR BLADE COOLING

Daniel J. McCarty, Drexel Hill, and Edward H. Lutz, Norwood, Pa., assignors, by mesne assignments, to the United States of America as represented by the Secretary of the Navy

Original application June 12, 1956, Ser. No. 591,002, now Patent No. 2,906,494, dated Sept. 29, 1959. Divided and this application July 31, 1959, Ser. No. 841,425.

3 Claims. (Cl. 253—39.15)

This application is a division of co-pending application Serial No. 591,002, filed June 12, 1956, now Patent No. 2,906,494, granted Sept. 29, 1959.

This invention relates to means of controlling the local temperatures in turbines.

In order to insure the maximum efficiency of any turbine, gas or steam, it is necessary that the turbine operate at a constant uniform temperature. Solid type blading is often used in a turbine where the maximum temperature of the passing gas or steam is not too high. However, in modern day turbines, the temperatures of the fluids passing through the turbine are very high and cooling means for the various parts of the turbine must be provided to reduce the temperature thereof. Even with such cooling means, "hot spots" develop, due to the very high temperatures of the passing fluids, in isolated sections of the turbine that are difficult to cool.

A further disadvantage occurs with the cooling systems presently in use in that the amount of cooling is kept constant and no automatic compensation is made for differences in temperature between the blading and the passing fluids. As a result of this, at times the turbine runs at something less than maximum efficiency.

An object of this invention, therefore, is a cooling system for turbines wherein the danger of hot-spots is eliminated.

A further object of this invention is a system wherein a turbine runs at maximum efficiency by operating at a constant temperature under varying conditions.

A still further object of this invention is a cooling system which automatically controls the amount of cooling fluid passing through the hot turbine.

These and additional objects will be readily apparent to those skilled in the art from a perusal of the following disclosure and an examination of the enclosed drawings wherein:

Figure 1 is a cross-sectional view of a turbine showing the details of the cooling systems.

Figure 1A is a cross-sectional view of a fragment of a turbine complementary to that of Figure 1 showing a modification of the invention.

Figure 2 is a modification of the location of the cooling system control unit.

Figure 3 is a modification of the cooling system control unit and valve.

Figure 4 is a cross-sectional view along section lines 4—4 of Figure 1, and

Figure 5 is a further modification of the cooling system control unit.

In Figure 1, a turbine 1 comprises a solid rotor, 2, having on its periphery a plurality of blades 4. Encompassing the turbine is a casing 3 providing a housing for the turbine rotor and means for suspending the stator blades.

Forward and rear rotor blades 4 are hollow, which construction is well known. Forward blades 4 are divided by a transverse wall 5 commencing from the root of the blade and terminating just short of the tip 44 thereby

2

dividing the blade into two compartments 46 and 47, with an open passage 48 at the tip joining the compartments.

Within each blade a build up portion 6', extending from the root, has a plurality of ports 6 therein; one port for each compartment.

A bimetallic leaf 8 is secured at its mid-point to the wall 40 and extends over both ports 6. A coolant feed line 41 leads into one of the compartments via passage 14 and return line 42 is connected to the other of the compartments via passage 13.

In the stator blade 21, Figures 1 and 4, preceding the above turbine rotor stage, the blades are secured to shroud ring 27 and to the inner ring 43. The blade is divided into two compartments by a transverse partition

15 22 in which is provided a passage 23. The port is covered by a bimetallic strip 24 fastened at one end by a rivet 60 to the partition wall. A conduit 15 feeds cooling fluid into one of the compartments while conduit 16 returns the fluid back to the source.

20 20 A further modification of the valve means is shown in Figure 1A. In the rotor blade 4 a partition wall 12 divides the blade into two compartments 49 and 51 with a passageway 52 at the tip 44 of the blade connecting the compartments, while in the stator stage, blade

25 21 has a partition wall 25 dividing the blade into two similar compartments. Conduits 17 and 18 lead into the compartments at the root of the stator blade; conduits 9 and 10 lead into the compartments at the root of the rotor blade. Both compartment entry ports are covered

30 by a bimetallic element, element 11 in the rotor blade and element 26 in the stator blade. Each element is connected at its mid-point to its respective partition wall and its respective blade root 56 and 59.

Figure 2 illustrates a further modification of the valve means. Conduit 19 feeds in and conduit 20 discharges from the compartments 54 and 55, respectively; recessed adjacent an opening of one of the compartments is a bimetallic element 28; the other opening is not serviced with a bimetallic element and fluid passes freely through 40 the port.

In Figure 3 a further modification of the valve means is shown. The blade root or shroud ring has attached thereto the bimetal element 29 via a rivet 33. Feed line 32 terminates in a countersunk section 31 and a matching truncated nipple or valve element 30 is fastened to the portion of the bimetal element 29 covering the port. When the opening is closed, recess 31 accommodates valve element 30 preventing a passage of fluid; when the valve is open, element 30 is clear of the recess 31 providing an opening for the passage of fluid.

50 50 Figure 5 shows still a further modification. In this figure, conduits 36 and 37 are connected to the two compartments 57 and 58. Valve 50 is maintained in its recess by the action magnet 34 which functions as a valve seat and has an aperture 64 through which cooling fluid 55 from conduit 36 enters compartment 57. When the temperature of the fluid increases, the magnet loses some of its retaining properties and the spring 35 forces the valve 50 to its open position. The spring 35 is secured by means of rivets 68 and 70 to the valve 50 and partition wall 66, respectively. A passage 66 in wall 70 is provided to interconnect compartments 57 and 58.

60 60 The cooling fluid may be connected to any type of cooler 38 well known in the art or it may be directed externally of the turbine to atmosphere if the fluid is air.

Operation

70 70 All of the modifications illustrated, except that of Figure 5, operate basically in the same manner. If the temperature of the cooling fluid is low, the bimetallic element in each of the modifications covers the fluid inlet port or the element covers both the inlet and outlet ports,

When the temperature of the cooling fluid starts to increase above a predetermined range of temperatures, the bimetallic valve slowly starts to turn thus slowly uncovering the associated passage. A similar action occurs if a hot spot begins to develop in one of the blades. The bimetallic element/s of that blade further open the valve allowing additional cooling fluid to circulate through the blade, thus cooling it more than the adjacent blades.

In a steady state condition, the valves are partially open allowing a percentage of maximum flow to go through. If the valves begin to heat up, the bimetallic valves open further allowing additional fluid to pass through; if the valves tend to cool somewhat, the bimetallic valves tend to close thereby restricting the flow of fluid and the blades have a tendency to return to the temperature of the steady state condition.

In the modification of Figure 5, the magnet 34 functions in a manner similar to the bimetallic valve. The magnetic action fluctuates under the action of the heated fluid thereby allowing the bias action of the spring to come into play.

While several modifications of the basic temperature control system are shown in Figure 1, it is of course understood that one type of valve means may be used for both the stator and rotor blades or the blades of the rotor may have one type of bimetal and valve and the blades of the stator have another modification of the bimetal and valve.

Obviously many modifications and variations of the present invention are possible in the light of the above teachings. It is therefore to be understood that within the scope of the appended claims the invention may be practiced otherwise than as specifically described.

What is claimed is:

1. In a turbine having a hollow, fluid-cooled blade with said blade having a tip portion and a root portion, a partition wall in said hollow blade extending substantially longitudinally thereof from said root portion

and thereby forming a pair of compartments within said hollow blade, said partition wall terminating in advance of said tip portion of said hollow blade to thereby provide a passageway between said pair of compartments, said 5 hollow blade having a fluid inlet in said root portion to accommodate the entry of cooling fluid into one of said compartments and having a fluid outlet in said root portion to accommodate the discharge of cooling fluid from the other of said compartments, a magnetic valve 10 seat carried within said one compartment, and a spring biased valve member carried with said one compartment and being movable between open and closed positions relative to said magnetic valve seat in response to changes in the temperature of the cooling fluid flowing through 15 said hollow blade to thereby maintain said blade at a substantially constant predetermined temperature.

2. In a turbine as claimed in claim 1 wherein said magnetic valve seat is carried within said one compartment at the root portion of said blade.

20 3. In a turbine as claimed in claim 1 wherein said valve member is carried by a spring one end of which is rigidly connected to said partition wall and the opposite end of which is rigidly connected to said valve member, said spring being operable to constantly urge 25 said valve member toward said open position.
